[57] CLAIM

The ornamental design for a rope stake top, as shown and described.

DESCRIPTION

FIG. 1 is a perspective view;
FIG. 2 is a front view, the rear view being a mirror image;
FIG. 3 is a right side view;
FIG. 4 is a top view; and,
FIG. 5 is a left side view.

The broken line showing of the lower part of the stake in FIGS. 1-5 is for illustrative purposes only and forms no part of the claimed design.
